UNITED STATES PATENT OFFICE.

THEODORE A. B. PUTNAM, OF NEW YORK, N. Y., ASSIGNOR OF ONE-HALF TO
WILLIAM COURTENAY, OF SAME PLACE.

UNDERGROUND CONDUIT.

SPECIFICATION forming part of Letters Patent No. 335,091, dated January 26, 1886.

Application filed September 24, 1885. Serial No. 177,989. (No model.)

To all whom it may concern:

Be it known that I, THEODORE A. B. PUTNAM, a resident of the city, county, and State of New York, have invented certain new and 5 useful Improvements in Underground Conduits for Electric Wires, of which the following is a specification.

The object of my invention is to provide a conduit so constructed that various wires can 10 be carried in the same conduit and be free from the induction of currents on one another; that wires of one class or company can occupy a separate compartment and be manipulated without injury to other wires; that the wires 15 can be branched easily through pipe attachments or branch conduits; that access can be readily had from the street-surface; that wires can be drawn in at any time by means of a device, hereinafter described, in permanent attachment to the conduit without injury or removal of those in possession, and that these 20 features can be accomplished and constructed in a rapid and not too costly manner.

I have shown in the drawings six separate 25 compartments, designed for telephone, telegraph, district, fire, quotation, and electric-light service.

My invention consists in the combination of devices hereinafter particularly described, and 30 as more at length recited in the claims.

There are two plates illustrating the invention, comprising Figures 1, 2, 3, and 4. Fig. 1 is a longitudinal elevation showing the connection of one section to another, with an interior view of the arrangements of same. Fig. 35 2 shows a plan view with chamber for communicating to the surface. Fig. 3 shows a cross-section with interior elevation. Fig. 4 shows a perspective view of a branching section and method of prolonging the same, with 40 means of access.

Similar letters indicate similar parts.

I construct the conduit shown in the drawings preferably of iron; but any suitable material can be used. The sections A are cast of 45 any suitable length and capacity, with horizontal partitions B of any number cast or inserted in the same, and forming separate compartments for the reception of wires. The partitions or screens B are connected electrically

to earth by being a part of the conduit, and form, as shown, compartments 1 2 3 4 5 6. These sections A are made with flanged rims to meet together, and secured by bolts passing through both flanges. When these are set up, 55 inclosing an intervening packing, a secure and tight joint is formed, and a continuous uniform conduit is obtained with its several compartments.

Access is obtained to the wires within the 60 conduit, and their direction changed to any point outside of the same, as follows: Right-angled branching sections E are made, having flanged rims at the four terminations to engage those of sections A. Two of these 65 terminal entrances are shown open in the drawings, Fig. 4. When such entrances are not joined to main sections A, they may be closed by a suitable metal plate. The arrangement of the partitions B is continued throughout 70 all portions of the sections E, so as to coincide with the level of same in sections A.

Between the two adjacent vertical faces or 75 walls of the branch section E, at the diametrically-opposite angles thereof, is cast or otherwise formed or provided a base plate or web, D, extending from the lower edge of one of said adjacent walls exteriorly to the other, as shown in Figs. 4 and 2.

H is a drum or cylinder, which is fitted down 80 upon the plate D, being cut away vertically and laterally to fit upon and against the side and top walls of the section E, thus constituting a chamber intermediate the angle ends of the said section, as shown in Fig. 2.

In the adjacent side walls of the section E, within and forming part of such chamber, are cut the openings C, of dimensions suitable to admit of the passing of the hands and arms through them. These openings C are one opposite or opening into each of the compartments constituted in the interior of the conduit, as hereinbefore described, and thus constituting communication between each compartment and the chamber formed by the drum 85 D. The drum is intended to extend upward to the surface of the street or ground, where a man-hole cover may be provided.

In the vertical section-walls within the chambers D are the openings c, through which 90

wires may be conducted from the compartments upward of the chambers to the ground-level for the purpose of entering buildings, &c. These openings *c* are, several of them, 5 arranged to form communication between each compartment and the chamber D, as shown in Fig. 4.

In combination with the conduit and branch section, constructed as described, I employ the 10 following-described devices to facilitate the introduction of the wires into the several compartments and manipulating them therein. A rope or traveler, I, beginning in compartment 1 of section E, (left hand,) passes through 15 this compartment to the other section E; then, turning on a pulley-wheel, *f*, secured in position, passes through partition B, and takes a return direction through compartment 2, and similarly back and forth over pulley-wheels 20 *f*, through the compartments 3 4 5 6, until it reaches the first section E, where it passes through the partitions B, where it is joined in compartment 1 and so made endless. In section 1 the rope I passes around a suitable 25 wheel, F, the axle of which is prolonged to the sides of the section, so as to be moved by a movable winch outside of the conduit and within the chamber D, as L, Figs. 2 and 3. When the wheel F is revolved, motion is im- 30 parted to the rope I in every compartment in a direction according to the motion of the wheel F. It is therefore evident that wires may be drawn through the length of any compartment by being simply attached to the rope 35 or traveler, and that all wires may be drawn through in one and the same direction in all the compartments by simply giving a reverse rotation to the winch L for each alternate com-

partment, beginning at the top or bottom compartment. The workman in the chamber D 40 may thus seat any number of wires in each compartment by simply attaching each wire to the traveler and operating the winch. The rope I may be arranged to travel on the floor of each compartment, running in an open 45 groove, if required, and may have loop attachments, to which wires may be fastened, and drawn into any of the compartments by the travel of the rope I.

I claim as my invention—

1. The combination, with the conduit A, 50 having horizontal partitions B, dividing the conduit into several compartments, one above the other, of the branch section E and the web piece or plate D, arranged as described, 55 together with the drum or cylinder H and the series of apertures C and *c* in the walls of the branch section within the man-hole chamber, and affording communication, as described, between each separate compartment 60 of the conduit and said chamber, as and for the purpose specified.

2. The combination, with the conduit A, 65 divided into a vertical series of compartments by partitions B, and having branch section E, web D, cylinder H, and openings C, one from each compartment into the man-hole space comprised by said cylinder, of the endless rope or traveler I, running back and forth through the several compartments, and having the pulleys *f* and the winch L within the man-hole chamber, as and for the purpose set forth.

THEODORE A. B. PUTNAM.
